CLAIM

The ornamental design for a LP cover for recreational vehicles, as shown and described.

DESCRIPTION

FIG. 1 is a front, left perspective view of an LP cover for recreational vehicles showing my new design;

FIG. 2 is a right side view thereof, the left side being a mirror image view minus the lid closure mechanism; and,

FIG. 3 is a top view thereof.

In the drawings, the broken lines in FIGS. 2 and 3 depict portions of a vehicle that form no part of the claimed design.
